UNITED STATES PATENT OFFICE.

HARRY J. WARTHEN, OF WASHINGTON, DISTRICT OF COLUMBIA.

APPARATUS FOR CONTROLLING THE SPEED OF RAILROAD-TRAINS.

1,090,361.

Specification of Letters Patent. Patented Mar. 17, 1914.

Application filed June 24, 1912. Serial No. 705,620.

To all whom it may concern:

Be it known that I, HARRY J. WARTHEN, a citizen of the United States, residing at Washington, in the District of Columbia, have invented an Apparatus for Controlling the Speed of Railroad-Trains, of which the following is a specification.

The invention shown and described in this application is part of a system for controlling the operation of railroad trains forming the subject-matter of a companion application for patent filed June 24, 1912, Serial No. 705,618.

The present invention relates especially to the means employed for stopping a railroad train automatically when it exceeds a predetermined rate of speed, to thereby provide for limiting the operation of the train under certain conditions.

In the present instance mechanical devices, including a governor and electric switches, are employed for controlling an electric circuit through a solenoid, which latter operates to open and close a valve of the air-brake system or steam-supply, according to the speed of the train; the electric switches being arranged to also affect the circuit in case any essential part of the governor device and its connections should become broken or disarranged, all as herein-after fully described and specifically set forth in the appended claims.

In the accompanying drawings; Figure 1 is a general view of the means employed for carrying out my present invention. Fig. 2 is a sectional view on the line 2—2 of Fig. 1, to show the belt connection and co-operating parts. Fig. 3 is an enlarged detail view of the main electric-switch, showing the operation thereof under different conditions.

In carrying out my invention I employ in the first place a conventional form of governor device 5, in which the vertical spindle 6 is geared to the driving-shaft 7 through the intervention of beveled pinions 8 and 9 on the spindle and shaft respectively, said driving-shaft being supported in a bearing 10 formed on the frame 10 of the governor device. In the present instance the driving-shaft 7, operating the governor, is driven from an axle 11 of the train or locomotive by means of a belt 12, which passes over pulleys 13 and 14 on the shaft and axle, respectively. The vertical spindle 6

works loosely through the pinion 8 and frame 10 of the governor, and at its lower end is connected to an electric switch-lever 15, pivoted in ears 10^b on the supporting-frame 10, and provided at its outer or free end with a weight 15^a, the purpose of which latter will be hereinafter explained. Near the outer end of this switch-lever is a flat portion 15^b (Fig. 3), which is adapted to move over a contact-plate 16, supported by a suitable bracket 17, said contact-plate being of such length and so disposed that the switch-lever will be in engagement therewith when the governor is at rest and when the spindle thereof is raised to a certain extent. For instance the length of the contact-plate may be such that the switch-lever will clear the upper end thereof when the governor indicates a speed of the train in excess of ten miles an hour, and, of course, by lengthening the contact-plate the maximum speed may be increased. Furthermore, the relation of the switch lever and contact-plate is such that should the spindle of the governor become broken or otherwise disarranged said switch-lever would drop below the contact-plate, and in order to insure this operation the lever is provided with the weight 15^a, hereinbefore referred to. When the switch-lever moves beyond the upper or lower end of the contact-plate the electric circuit, hereinafter described is broken, as will be understood.

The electric-switch above described is in a circuit from a battery 18, or other source of electric supply, one pole of which is connected to the lever, at its pivot-end, by a wire 19, and the other pole by wire 20 to solenoid 21, by wire 22 to electric-switch 23—24, and by wire 25 to contact-plate 16, whereby the solenoid will be energized when the electric-switches 15—16 and 23—24 are closed.

The switch-lever 23 is held in a normally raised, and therefore closed position, by means of a roller 26 at the outer end thereof resting lightly against the driving-belt 12, the lever being pivoted in ears 27^a of a supporting-bracket 27, and the contact-plate 24 attached to a standard 27^b on said bracket. As will be noted, therefore, this switch remains closed as long as the belt is intact or does not become slackened to any great extent to affect the operation of the driving-

shaft 7 of the governor. In case the belt should break or become excessively slack the switch-lever 23 would drop, thus opening this switch and by breaking the circuit cause the solenoid to become deenergized.

The solenoid may operate any mechanical devices to display a signal or operate a valve so as to indicate that the train is exceeding the maximum speed at which the governor devices are set. In the present instance the solenoid serves to operate a valve, which may be located in the steam-supply pipe leading to the cylinder of the locomotive-engine, or in the train-line pipe of the air-brake system. The core 21^a of the solenoid is connected to a pivoted lever 28 connected to the valve 29, the parts being so arranged that the valve will be tightly closed when the solenoid is energized and opened when said solenoid is deenergized.

The operation of the devices will be readily understood from the foregoing description, in connection with the accompanying drawings, for as long as the train proceeds at a speed at which the governor maintains the switch-lever 15 in contact with the plate 16 the circuit through the solenoid is closed and the valve 29 thereby held closed, but as soon as the speed of the train is such that the governor moves the switch-lever 15 beyond the contact-plate 16 the circuit is broken, the solenoid deenergized and the lever operates to open the valve, and if the valve is in the train-line pipe of the air-brake system the air brakes on the train are applied. The solenoid is also deenergized in case either one of the switch-levers 15 or 23 should drop from any cause.

It will be understood, of course, that though I have herein shown and described a solenoid for operating the lever 28 any

other electrical device may be employed for the purpose.

Having thus described my invention, I claim:

1. In an apparatus for controlling the speed of railroad trains, an electric circuit, a solenoid and an electric-switch included in said circuit, a governor geared to a driven shaft of the train and operating the switch, and a second electric-switch in the aforesaid circuit held normally closed by a part of the governor mechanism; together with means operated by the solenoid.

2. In an apparatus for controlling the speed of a railroad train, an electric circuit, a solenoid and an electric-switch included in said circuit, a governor connected to the electric-switch for operating the same, a belt forming a driving connection for the governor, and an electric-switch in the aforesaid circuit held normally closed by the belt; together with means operated by the solenoid.

3. In an apparatus for controlling the speed of a railroad train, an electric circuit, a solenoid and an electric-switch included in said circuit, a governor connected to the electric switch for operating the same, a belt forming a driving connection for the governor, a second electric-switch included in the aforesaid circuit and comprising a contact and companion lever, the latter being pivoted and provided with a roller bearing against the belt to maintain said switch closed, and means operated by the solenoid.

In testimony whereof I have signed my name to this specification in the presence of two subscribing witnesses.

HARRY J. WARTHEN.
